METAL HEEL COMPANY, OF BOSTON, MASSACHUSETTS, A CORPORATION OF
MASSACHUSETTS.

HEEL FOR FOOTWEAR.

1,399,346.

Specification of Letters Patent.

Patented Dec. 6, 1921.

Application filed November 10, 1920. Serial No. 423,014.

To all whom it may concern:

Be it known that I, STERGOS JAMOPOULOS, a subject of the King of Greece, residing at Boston, in the county of Suffolk, in the State 5 of Massachusetts, have invented a certain new and useful Improvement in Heels for Footwear, of which the following is a specification, reference being had to the accompanying drawings.

10 This invention has special relation to ladies' footwear of the type in which hollow, metallic, heels are used and my present purpose is to provide novel and cheap means for securing such heels to the soles of such foot- 15 wear.

In the accompanying drawings the Figure 1 is a side elevation and Fig. 2 is a central, vertical, sectional, view of a heel embodying my present improvement; said Fig. 2 being 20 taken at the line 2—2 of Fig. 3, which latter is a top or plan view of the complete heel. In Fig. 4 I have illustrated, in plan, the blank from which is to be formed, by suitably bending the same, a cup or recess for a 25 nut used in securing the heel to the heel plate. Fig. 5 shows a slightly modified form of plate f.

In these drawings the letter a indicates the heel proper as a whole, said heel being 30 made hollow and, preferably, of aluminum in order that it may be of light weight.

Near the lower portion of the heel is a partition b which is drilled or cored to receive a screw c and said heel is cupped into 35 lower end portion to receive a washer d of leather, or the like material, to which may be tacked or cemented a lift e of leather or other resilient material which will serve as the tread portion of the heel.

40 Seated in the otherwise open upper portion of the heel a is a thin metal plate f which is provided with a plurality of small holes g which are designed to receive tacks by means of which the plate f may be fixedly 45 secured to the heel portion of the shoe sole. By preference the plate f is formed with circumferential notches h that are adapted to register with and fit over certain lugs i that are formed integral with the heel a. 50 These lugs extend up from the marginal depressed seat j around the cavity of the heel.

The screw c, which I have already referred to, extends upwardly in the heel a and its threaded end portion engages a nut k, which 55 is mounted directly in a depression a', as

seen in Fig. 5 of the drawings, or in a pocket m which is attached to plate f, which I will now describe specifically.

Said pocket is formed from a single piece blank of sheet metal (see Fig. 4) consisting 60 of a rectangular portion m', which is outlined by dotted lines in said Fig. 4, having radial portions n, n', n² and n³ which are adapted to be folded upward into rectangular relation to the portion m' as will be best 65 understood by reference to Figs. 2 and 3 of the drawings; the portion m' is provided with an opening o through which the screw c may pass in order to engage with the nut k which, it is assumed, is seated in the pocket 70 m. The radial portions n, n', n² and n³ are formed, respectively, with radially projecting tongues p, p', p² and p³ which are adapted, respectively, to be passed through openings q, q', q² and q³ in plate f, and to be 75 clenched down upon said plate as seen in Fig. 2, thus uniting fixedly plate f and the plate m' upon which the nut k rests. Any appropriate means (not shown) may be employed for securing the nut k on its seat in 80 the cup or depression. By thus forming the nut-supporting pocket m I am able to utilize very thin sheet material for the plate f, thereby reducing the cost of said plate when compared with certain relatively thicker 85 plates now in common use which are simply drilled and tapped to receive the threaded end portion of the clamping screw.

In the operation of attaching a heel to a shoe by my described means, the plate f is 90 tacked to the heel portion of the shoe, the nut k having first been placed in the pocket m or a', as the case may be. The heel a is then placed in proper position on plate f and screw c is passed upward, through hole 95 b, and screwed home in said nut, thereby clamping the heel securely to plate f and to the shoe.

Having thus described my invention, I claim,

1. A heel-fastening device comprising a plate securable to the heel portion of a boot or shoe and formed with a central group of apertures, and a cup formed with tongues extending through and secured in said apertures and adapted to hold a nut in position to engage with said plate. 105

2. A heel-fastening device comprising a plate formed with peripheral notches, a series of marginal holes for receiving fasteners 110

- to secure it to the heel portion of a boot or shoe, and a central group of holes; in combination with a heel having lugs fitted in said peripheral notches, a cup formed with 5 tongues extending through and clenched in said central apertures respectively, a nut in said cup, and a screw engaged with said heel and in position to secure the latter to said nut.
- 10 3. In a heel-fastener, a plate securable to the heel portion of a shoe-sole and formed with a central opening and with holes at opposite sides of said central opening; in

combination with a cup formed with down-turned tongues, the body of said cup extending down through said central opening while said tongues extend down through said opposite holes and are clenched under said plate, said cup having an aperture in its bottom through which a screw can extend, the 15 interior of the cup being formed to fit about the edges of a nut and hold the latter in position to receive a screw through said aperture.

STERGOS JAMOPOULOS.
